UNITED STATES PATENT OFFICE.

ADOLPH K. BRAUER, OF LOS ANGELES, CALIFORNIA.

DESIGN FOR A SPRINKLER-BODY.

52,427.

Specification for Design.

Patented Sept. 17, 1918.

Application filed October 8, 1917. Serial No. 195,466. Term of patent 14 years.

To all whom it may concern:

Be it known that I, ADOLPH K. BRAUER, a citizen of the United States, residing at Los Angeles, in the county of Los Angeles and State of California, have invented a new, original, and ornamental Design for Sprinkler-Bodies, of which the following is a specification, reference being had to the accompanying drawing, forming part thereof.

Figure 1 is a side elevation of the sprinkler body, showing my new design.

Fig. 2 is a plan view of the sprinkler body.

Fig. 3 is a view of said sprinkler body from the right of Fig. 1.

Fig. 4 is a view of said sprinkler body from the left of Fig. 1.

This design is adapted for sprinklers having covers and bases, as indicated in the drawing by a spike base in solid lines and a cover in dotted lines.

I claim:

The ornamental design for a sprinkler body substantially as shown.

ADOLPH K. BRAUER.

Witness:

JAMES R. TOWNSEND.
